UNITED STATES PATENT OFFICE.

ROBERT HARRIS HARMAN, OF CHESTER, VERMONT, ASSIGNOR OF ONE-HALF TO
GEORGE L. DAWLEY, OF WESTMINSTER, MASSACHUSETTS.

SELF-LEVELING BERTH.

1,180,034.

Specification of Letters Patent. Patented Apr. 18, 1916.

Application filed November 12, 1915. Serial No. 61,180.

To all whom it may concern:

Be it known that I, ROBERT H. HARMAN, a citizen of the United States, and a resident of Chester, in the county of Windsor and 5 State of Vermont, have invented a certain new and useful Improvement in Self-Leveling Berths, of which the following is a specification.

My present invention relates generally to 10 berths for use on ship-board, and more particularly to a self-leveling berth, my object being to provide a berth having a relatively short swinging movement as compared to that of the adjacent tilting or swinging 15 parts, and having in addition thereto a laterally tilting movement by which it is maintained in a level position at all times.

A further object of my invention is to provide a construction in which the berth, movable as above described by certain pivoted parts of its support, is supported, or its weight sustained, by other and more stable connections which in turn actuate the pivoted parts as will be hereinafter shown.

Further objects of, and the advantages resulting from, my present improvements, will be better understood from the following description thereof, reference being made to the accompanying drawings, forming a part 30 of this specification, and in which—

Figure 1 is a perspective view illustrating the practical application of my invention. Fig. 2 is a transverse vertical section through the berth and its frame, and 35 through the swinging frame, which operates the same. Fig. 3 is a perspective view of one end of the apparatus. Fig. 4 is a perspective looking at one end of the base of the berth frame. Fig. 5 is a similar view looking at 40 one end of the lower portion of the berth itself, and Fig. 6 is a vertical longitudinal section taken through one end portion of the apparatus.

Referring now to these figures, I have 45 shown in Fig. 1, a pair of spaced rigid uprights A, which may be either in the nature of boxed supports attachable either at the base thereof to the floor of a state-room on shipboard, or at the sides, to the side walls 50 of the state-room, or in the nature of the

walls of the state-rooms themselves, each of these uprights A in either case supporting one of the upright ends B' of a swinging frame, the lower horizontal portion B of which extends between the lower ends of the 55 upright portions B' and between the rigid upright supports A before mentioned.

Centrally of their upper ends, the upright end portions B' of the swinging frame are pivoted upon bolts B² secured, as best seen 60 by reference to Fig. 6, to the support A, these upright end portions B' being provided with upper and lower rectangular openings B³ and B⁴ respectively, receiving rectangular blocks C and D respectively, the 65 upper block C being centrally pivoted adjacent its upper end by means of a pivot member C' secured within the support, and which may be in the nature of a screw as clearly shown in Figs. 3 and 6, whereby to 70 adapt the block C to assist in the support of the end upright portions B' in connection with the uprights A, which end portions it will be noted are not otherwise secured except by the pivot bolts B².

The lower blocks D are centrally pivoted adjacent their upper ends upon pivot bolts D' which, like the pivot bolts B² before referred to, extend from the support A as clearly seen in Fig. 6. Each of the 80 blocks D, the upper and lower edges of which slidably engage the upper and lower walls of the rectangular opening B⁴, in substantially the same manner as block C engages the upper and lower walls of the rectangular opening B³, is thus guided in its movement upon its pivot bolt D', by the before mentioned frame in its movements, including the end upright portions B'.

At its lower end, each of the rectangular 90 blocks D is provided with a horizontal portion D² which, as clearly seen in Figs. 3 and 6, overlies one end of the lower horizontal portion B of the swinging frame, in spaced relation thereto, so as to receive and support 95 one end of the berth-frame E having side and end pieces and having its base E² provided with laterally elongated slotted openings E² adjacent its opposite ends as clearly seen in Fig. 4, the end portion of the berth- 100

frame E disposed upon the lower horizontal portions D² of the block D, being secured thereto by means of screws or like fastening members E³ as clearly seen in Fig. 6.

- 5 Adjacent each of its ends, the lower horizontal portion D² of the swinging frame, is provided with a cross piece B⁵ supporting adjacent its opposite ends, upwardly projecting rollers B⁶, which when the parts are 10 assembled project upwardly through the laterally slotted openings E² of the base E' of the berth-frame E before described, in order to support the weight of the berth itself, which berth to this end has a lower 15 plate or the like F, seen particularly in Figs. 2 and 6, which as shown in Fig. 5, has a transverse track F' adjacent each end provided with grooves F² which receive the rollers B⁶. The berth may, in addition to 20 its lower plate F, include a spring F³ and a mattress F⁴ as best seen in Figs. 2 and 6, and if so desired the track F' may be formed directly upon the spring F³. Thus during 25 swinging movement of the frame including the horizontal portion B, which in the use of the berth constitutes a rack for the reception of the occupant's apparel, luggage and the like, as indicated in Fig. 1, moves the block D upon its pivot bolt D', swinging 30 the latter in a degree considerably reduced as compared to the extent of swinging movement of the swinging frame itself, the berth-frame E, secured to the horizontal extensions D² of these blocks, following the movements of the blocks. At the same time, the 35 weight of the occupant of the berth lying directly thereon, is supported from the swinging frame through the rollers B⁶, with respect to which the berth has movement 40 within the limits of slots E² so that the blocks D are relieved of all unnecessary strain, permitting ready and free movements thereof, under the guidance of the 45 swinging frame.
- I am thus enabled to provide a berth for use on ship-board capable of maintaining a level position at all times, and the movement of which will be ready and free under all conditions and of considerably less extent than the swinging or tilting movements of the parts utilized to actuate the same and the stationary parts of the ship.
- As before stated, the upright end supports A which are rigid in their nature, may be 50 either portions of the state-room walls, or in the nature of separate uprights attachable either at their lower ends to the state-room floor, or at their sides to the state-room wall, and in this latter form as well as where constituted by a portion of the state-room walls, I prefer that the supports be boxed in, by the provision of front plates A' detachably held to cover the upright end portions of the swinging frame, and the supporting and 55 tilting blocks C and D, and in this way con-

ceal from view practically all of the operating parts.

I claim:

1. In a self-leveling berth, the combination of a swinging frame having guide openings, pivoted supports disposed within said guide openings and actuated in their pivotal movements by the said swinging frame, a berth, and a berth-frame in which the berth is disposed, supported by and movable with, 70 said pivoted support.

2. In a self-leveling berth, the combination of a swinging frame having guide openings, pivoted supports disposed within said guide openings and actuated in their pivotal movements by the said swinging frame, a berth movable with respect to, and supported by, said swinging frame, and a berth-frame in which the berth is disposed and with which it is movable, supported by and movable with said pivoted supports. 80

3. In a self-leveling berth, the combination of a swinging frame, pivoted supports actuated in their pivotal movement by the said swinging frame, a berth frame supported by and movable with said pivoted supports, and provided with slots, rollers carried by the swinging frame and projecting upwardly through the said slots of the berth-frame, and a berth disposed within 95 and movable with said berth-frame, and in contact with and supported by, said rollers. 90

4. In a self-leveling berth, a swinging frame including upright end portions having rectangular slots, blocks disposed within 100 said slots and of substantially reduced width as compared to that of said slots, each of said blocks having one edge in engagement with one wall of its slot whereby to control the pivotal movement of the blocks on swinging movement of the frame, a berth-frame secured to, and supported by, said blocks, and a berth disposed within, and movable with, said berth-frame. 105

5. In a self-leveling berth, the combination of a swinging frame, pivoted supports actuated in their pivotal movement by the said swinging frame, a berth frame supported by and movable with said pivoted supports, and provided with slots, rollers 110 carried by the swinging frame and projecting upwardly through the said slots of the berth-frame, and a berth disposed within and movable with said berth-frame and in contact with and supported by said rollers, 115 said berth including grooved transverse tracks receiving the said rollers. 120

6. In a self-leveling berth, a swinging frame including upright end portions having rectangular slots, blocks disposed within 125 said slots and of substantially reduced width as compared to that of the slots, each of said blocks having an angular extension and having one edge thereof in engagement with one wall of its slot whereby to control the piv- 130

otal movements of the block on swinging movement of the frame, a berth frame secured to and supported by the said angular portions of said blocks and provided with 5 slots, rollers carried by the said swinging frame and projecting upwardly through said slots, and a berth disposed within and mov-

able with, said berth-frame, and engaged and supported by said rollers.

ROBERT HARRISS HARMAN.
